TOY MAGNET CRANE

Henry W. Sauer, South Euclid, Ohio, assignor to
The Ohio Electric Mfg. Co., Cleveland, Ohio, a
corporation of Ohio

Original application March 24, 1932, Serial No.
600,939. Divided and this application January
29, 1934, Serial No. 708,795

3 Claims. (Cl. 46—37)

This invention relates to a toy magnet crane, and particularly to one having the general external appearance and many of the mechanical characteristics of larger devices such as might be used for handling scrap iron or the like.

The principal object of the invention is to provide a toy of the type indicated which will be entertaining and instructive and at the same time durable, cheap and accessible as to its operating parts.

Other and more limited objects will become apparent from the following description when taken in connection with the accompanying drawings in which Fig. 1 is a side elevation; Fig. 2 is a plan view; and, Fig. 3 is a detail section on a large scale taken centrally through the base and the lower platform.

Referring now to the drawings, the numeral 10 indicates a base on which is mounted a platform 11. Secured centrally to the platform 11 as by screws 12 are a pair of spaced uprights 13 converging to contact at the top, as best seen in Fig. 2. Journaled in the uprights 13 is a winding drum shaft 14. Journaled in the uprights 13 adjacent the top is a pulley and shaft 16. Pivotally connected to projections 17 on the uprights 13 is a crane member 18 which is provided with a pulley 19 at its opposite end and with a transverse pin 20 extending between the two parts thereof adjacent the highest point. Mounted upon the shaft 14 is a winding drum 21 upon which is wound a cable 22 which passes over the pulleys 16 and 19 and terminates in a hook 23 upon which is suspended a magnet 13. Mounted upon the shaft 14 is a worm gear 24 which meshes with a worm 25 operated by a hand crank 26. By turning this crank in opposite directions, the magnet may be elevated or lowered. A rod or wire 27 provided at each end with a hook connects the pin 20 with the upper extremity of the members 13 passing through an opening 28 therein. Mounted upon the platform 11 on the portion thereof which overhangs the base 10 is a transformer 29. The output of the transformer is connected in series with the magnet 13 and a switch 30 carried by a handle member 31 mounted upon and spaced above the platform 11. The member 31 is mounted on the platform by a vertical portion 31a and an attaching portion 31b which is secured to the platform thereby spacing the handle 31 above the platform. Current is supplied to the transformer 29 by suitable extension cord 32 connected to the house current and to the primary winding of the transformer 29. Current is sup-

plied from the transformer to the magnet 13 by means of a flexible cable 33. The cable 33 contains conductors 33a and 33b. Conductor 33b is connected to one side of the secondary winding of the transformer 29 while that 33a is connected to one side of the switch 30. The other side of the switch 30 is connected to the other side of the secondary winding by conductor 33c. The base 10 and platform 11 may be made of aluminum or similar light metal and the platform may have in addition to the transformer a counter-balancing member 34 of heavier metal, such as lead, connected thereto by the screw 35. The platform and base will be rendered easily movable with respect to each other by ball bearings 36, as clearly indicated in Fig. 3.

The lifting magnet employed is preferably of the construction shown in my copending application Serial No. 600,939, filed March 24, 1932, of which this is a division.

In view of the foregoing it will be clear that I have provided a device which is well adapted for its intended purposes and while I have shown and described a preferred embodiment, I wish it understood that I am limited only in accordance with the appended claims and the prior art.

Having thus described my invention, what I claim is:

1. In a device of the class described, a base, a platform mounted for rotation on said base, a pair of spaced uprights mounted on said platform and converging toward the top, a winding drum journaled between said uprights, means including a hand crank for rotating said winding drum, a crane member pivoted adjacent said platform, means connecting said uprights with said crane member for positioning the latter, an electromagnet, a cable connecting said magnet and said winding drum, there being pulleys carried by said uprights and said crane member and said cable passing over said pulleys, a handle carried by said platform for rotating the same about said base, a switch carried by said handle at the platform end thereof, a source of current and conductors connecting said switch and said magnet in series with said source and both said handle and said hand crank extending in a direction opposed to that in which said crane extends whereby said handle and switch may be manipulated by one hand of the operator while the hand crank is manipulated by the other.

2. In a magnetic toy, a base, a platform mounted for rotation upon said base and having a por-

tion extending therebeyond, a crane mounted upon said platform and extending over the edge thereof in a direction opposed to said projection, a handle carried by said projection, a switch carried by said handle near the point of attachment thereof to said projection and means including a hand crank for manipulating said crane, said crank and said handle extending in the same direction whereby said handle and switch may be manipulated by one hand of the operator and said hand crank by the other.

3. In a device of the class described, a base, a platform mounted for rotation thereon, a handle mounted upon said platform for rotating the

same, a switch carried by said handle, an electric lifting magnet, means carried by said platform for suspending said magnet, a source of current and conductors connecting said switch and said magnet in series with said source said handle having a portion contacting and attached to said platform, an upright portion and a horizontal gripping portion, said switch being mounted on the gripping portion adjacent the vertical portion whereby said handle and switch may be manipulated by the same hand of the operator.

HENRY W. SAUER.
